DESIGN FOR A BOTTLE

Malcolm Wiesenfeld Lowenstein and Samuel Silberstein, Baltimore, Md.

Application August 22, 1941, Serial No. 103,050

Term of patent 7 years

To all whom it may concern:

Be it known that Malcolm Wiesenfeld Lowenstein and Samuel Silberstein, both citizens of the United States, residing at Baltimore City, State of Maryland, have invented a new, original, and ornamental Design for a Bottle, of which the following is a specification, reference being had to the accompanying drawing forming part thereof, and in which

Figure 1 is a view in perspective of the front of the bottle, showing our new design;

Figure 2 is a bottom view of the bottle shown in Figure 1, and

Figure 3 is a side elevation with parts broken away.

We claim:

The ornamental design for a bottle, substantially as shown.
